(57) **CLAIM**

The ornamental design for a heat transfer machine, as shown and described.

DESCRIPTION

FIG. 1 is a front perspective view of the heat transfer machine showing my design.

FIG. 2 is a bottom rear perspective view of the heat transfer machine.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an explode perspective view thereof; and,

FIG. 10 is a partially enlarged view of an area the heat transfer machine labeled 10 in FIG. 7.

The broken lines in the drawings are employed to show unclaimed portions of the heat transfer machine, and form no part of the claimed design.
